JOHN P. NORTHEY, OF TORONTO, ONTARIO, CANADA

RAIL JOINT

Application filed February 1, 1929. Serial No. 336,901.

This invention relates to rail joints in which angle bars or fish plates are secured to the rail ends at opposite sides by means of bolts passing through the angle bars and the web of the rail, and my object is to construct a strong and rigid joint of this type which will impose much less strain on the bolts than is now the case, thus rendering it much easier to secure and maintain a tight joint.

I attain my object by interlocking the upper edge of each angle bar with the underside of the rail head in such a manner that the rail head itself resists lateral displacement of the upper parts of the angle bars when the joint is set up, and by shifting the position of the bolts close to the lower parts of the angle bars, which shifting is made possible by the use of key bolts having heads elongated in the direction of the length of the rail, and their key slots so positioned that the keys approximate a horizontal position.

The invention is illustrated in the accompanying drawings in which

Fig. 1 is a side elevation of my improved joint;

Fig. 2 a cross section on a larger scale; and

Fig. 3 a plan view of one of the bolts.

In the drawings like numerals of reference indicate corresponding parts in the different figures.

In the drawings, 1 are the rail ends, and 2 the angle bars, which approximate in shape the commonly employed angle bars except as hereinafter set forth, and 3 are key bolts in the main of a type now known in the art.

The rails may be in cross section of any form commonly employed for a given size and weight, save for the fact that the under surfaces of the head of the rail are shaped to form anchorages for the upper edges of the angle bars 2; that is to say, they are so shaped that, when the angle bars are in position and engaged therewith, lateral displacement of the upper edges of the angle bars is restrained. Preferably these surfaces are concavely curved, as shown, and the upper edges 4 of the angle bars are shaped to rock therein. From this it follows that, when the angle bars are drawn to position by the bolts, the angle

bars rock on their upper edges. I am thus enabled to lower the position of the bolts 3 to give them more efficient leverage in drawing the angle bars to position, thus materially reducing the strain on the bolts themselves. 55 From this it follows that either the same strength in the joint may be obtained with a lighter bolt than usual, or increased strength be obtained with substantially the same dimensions of bolt as now employed. 60 I am enabled to position the bolts closer to the rail base than would otherwise be possible by employing key bolts as shown, each bolt being so positioned in the rail and angle bars that the key slot 5 is nearly parallel to the rail base. For convenience in driving, however, the slot is so positioned that the key 6 slightly inclines upwardly towards its driving end, which facilitates the driving of the key. A gib 7 will usually be employed in addition to the key. The head 8 of the bolt is of the elongated form shown, being approximately an ellipse with its major axis substantially parallel to the rail base. With this arrangement of the head and key, the 75 bolts may be positioned very close to the lower legs 9 of the L-shaped angle bars, their position being thus much lower than would be possible with ordinary bolts using nuts.

While the bolts longitudinally of the joint 80 may be positioned as in any ordinary joint, I prefer to position one bolt exactly at the point of junction of the two rails, half of the hole for the passage of the bolt being formed in the web on one rail and the other 85 half in the web of the other rail. With this arrangement the angle bars are closely held to the rail at the point where their support is most needed.

It will be found that a rail joint constructed 90 as described with the strain on the bolts relieved by the interlocking of the rail head with the upper edges of the angle bars and the leverage of the bolts increased, due to such anchoring and the position of the bolts, 95 the strength of the joint as a whole is materially increased and the liability of loosening at the joints materially decreased.

In this specification the term "angle bar" is used to include "fish plates" or "splice" 100

bars" of any form. So also while the anchorage of the angle bars is said to be with the heads of the rails, the arrangement is easily reversed and the angle bars anchored to the rail bases.

6 What I claim as my invention is:

1. In a rail joint, the combination of rail ends each having the under surfaces of its head shaped to form an anchorage for the 10 upper edge of an angle bar or fish plate to resist its outward displacement and having the upper surface of its base sloping downwardly and outwardly; an angle bar at each side of the rail adapted to engage said anchorage and at its lower side to bear against said downwardly and outwardly sloping surface; and key bolts passing through the angle bars and rail securing the parts together, said bolts having elongated heads positioned with their 20 longest axes substantially parallel to the rail base and also having their key slots positioned approximately parallel to the rail base.

2. In a rail joint, the combination of rail ends each having the under surfaces of its head concavely curved to form an under cut bearing for the upper edge of an angle bar; an angle bar at each side having a rounded upper edge adapted to rock in the aforesaid bearing; and key bolts passing through the 30 angle bars and rail securing the parts together, said bolts having elongated heads positioned with their longest axes substantially parallel to the rail base and also having their key slots positioned approximately parallel to the rail base.

35 Signed at Toronto, Canada, this 26th day of January, 1929.

JOHN P. NORTHEY.
